DESIGN FOR A COMBINED SACHET DOLL AND CONTAINER THEREFOR

Jean E. Vivaudou and Henry G. Lubin,
New York, N. Y.

Application August 29, 1940, Serial No. 94,719

Term of patent 7 years

To all whom it may concern:

Be it known that we, Jean E. Vivaudou and Henry G. Lubin, subject of Great Britain and citizen of the United States, respectively, and both residents of New York city, in the county of New York and State of New York, have invented a new, original, and ornamental Design for a Combined Sachet Doll and Container Therefor, of which the following is a specification, reference being had to the accompanying drawing, forming a part thereof.

Fig. 1 is a top plan view of a combined sachet doll and container therefor, showing our new design.

Fig. 2 is a side elevational view thereof taken from the right of Fig. 1; and

Fig. 3 is an end elevational view thereof from the top of Fig. 1.

We claim:

The ornamental design for a combined sachet doll and container therefor, as shown.

JEAN E. VIVAUDOU.
HENRY G. LUBIN.
